US00D814370S

(12) **United States Design Patent** (10) **Patent No.:** **US D814,370 S**
(45) **Date of Patent:** **** Apr. 3, 2018**

(54) **REMOTE CONTROL FOR UNMANNED AERIAL VEHICLE**

CPC H04N 7/15; H04N 7/142; H04N 5/232;
G05G 9/047; G06F 3/033
See application file for complete search history.

(71) **Applicant:** **LG ELECTRONICS INC.**, Seoul (KR)

Assistant Examiner — Dana K Weiland

(74) **Attorney, Agent, or Firm:** Birch, Stewart, Kolasch & Birch, LLP

(57) **CLAIM**

The ornamental design for remote control for unmanned aerial vehicle, as shown and described.

DESCRIPTION

1. Remote control for unmanned aerial vehicle

- 1.1 : Perspective
1.2 : Front
1.3 : Back
1.4 : Left
1.5 : Right
1.6 : Top
1.7 : Bottom
1.8 : Reference

(Continued)

The broken lines shown in Reproduction 1.8 depict environmental structure and form no part of the claimed design.

1 Claim, 8 Drawing Sheets
